[57] **CLAIM**

The ornamental design for a handle for a computer joystick, as shown and described.

DESCRIPTION

FIG. 1 is a rear isometric view of a handle for a computer joystick showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a front elevational view thereof.

The broken line drawings of a base for the handle for a computer joystick in FIGS. 1 and 4 are for illustrative purposes only and form no part of the claimed design.
